UNITED STATES PATENT OFFICE.

JOSEPH R. BLAINE, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

SHEET-GUIDE ADJUSTMENT.

1,345,742.

Specification of Letters Patent.

Patented July 6, 1920.

Application filed September 10, 1917. Serial No. 190,474.

To all whom it may concern:

Be it known that I, JOSEPH R. BLAINE, a citizen of the United States, residing at Oak Park, in the county of Cook and State 5 of Illinois, have invented certain new and useful Improvements in Sheet-Guide Adjustments, of which the following is a specification.

With few exceptions, it has been customary heretofore to feed the sheets individually to a printing press against substantially stationary gages or guides, so that during the travel of the paper it is necessarily stopped in its movement, at least momentarily, to secure the desired registration. In such cases the inertia of the paper must be instantly overcome when the grippers of the impression cylinder, which are constantly traveling at full speed, grasp the 20 sheet and transfer it to the cylinder. As will be appreciated, in a structure of that character the gages and grippers must operate with great precision to secure registration of the sheet and its transfer or 25 clamping to the rapidly traveling impression cylinder. In other words, when a sheet of paper is gaged and gripped in a press of this kind the stationary sheet has instantaneously imparted to it the full speed 30 of travel of the impression cylinder periphery, which renders accurate registration difficult if not impossible. Moreover, an instant before the grippers close, the guides must get out of the way, leaving the sheet 35 uncontrolled during this instant, affording a further chance for error in getting accurate register.

The present invention has for its primary object the provision of improved 40 means for securing accurate front and side registration of sheets fed to a printing couple, without stopping the sheet in its forward movement and at substantially the speed of the sheet taking grippers and the 45 impression cylinder whereby the full speed capacity of the press is utilized without its being limited in any way by the necessary registering process, while the correct registry of the sheet is in no way impaired by 50 the speed of sheet travel.

This object is accomplished according to my invention by providing a rotary sheet registering mechanism including gages traveling at the same speed as the grippers 55 on the impression cylinder and also includ-

ing means for frictionally seizing the front of the sheet at the point of delivery by the sheet feeder approximately adjacent the front gage and advancing the sheet to the said gage; also for similarly engaging the 60 side of the sheet and drawing it laterally to a side gage traveling with the sheet; and thereafter pulling off of the sheet an instant after the same has been taken by the grippers on the impression cylinder,—the 65 sheet registering mechanism and the grippers traveling in arcs approaching a point at which the path of the sheet is tangent to each whereby the front gage moves in its orbit into the path of the sheet as fed, and 70 after the sheet is registered and is seized by the grippers of the impression cylinder moves out of the sheet path to enable the sheet to pass on with the impression cylinder without interruption or interference. 75

In order that a complete understanding of the invention and more or less of the details of construction of a preferred embodiment of the invention may be fully understood, I have illustrated in a more or less fragmentary and diagrammatic manner one desirable embodiment of the invention in the accompanying drawings, which form a part of this application, and to which reference should be made. It is clear, however, that 80 the invention may be embodied in other and varied constructional forms without departure from the essence thereof, wherefore the drawing and description are to be taken in an illustrative rather than in an un- 85 necessarily limiting sense. 90

Figure 1 is a detail view in front elevation and partly in vertical section of the mechanism for imparting front register;

Fig. 2 is a detail view in side elevation 95 of the parts shown in Fig. 1;

Fig. 3 is an enlarged view showing in elevation the electromagnet for operating the front register mechanism in order to adjust the same;

Fig. 4 is a section on the line 4—4 of Fig. 3;

Fig. 5 is a side elevation partly in vertical section of the mechanism for imparting side register; and

Fig. 6 is a top plan view of the mechanism shown in Fig. 5.

The present invention is an improvement upon that forming the subject matter of my copending applications Serial Nos. 105,321 110

and 105,323. Although for the sake of clearness a general description of the same will be given, the claims herein are directed only to the features of improvement 5 over the constructions of my copending applications.

Having reference to Figs. 1 and 2 of the drawings, adjacent and in parallel relation to the impression cylinder (not shown) is 10 suitably mounted in the frame of the press a shaft 13 suitably driven at the same speed as the impression cylinder.

An arm 16 is keyed upon the shaft 13 by means of an extended boss 16^a whereon is loosely mounted a collar 17 held stationary by means of an arm 18 which takes over the fixed rod 19 extending between the side frames of the press. The stationary collar 17 bears cams 20 and 21 the purpose of which will hereinafter appear.

Loosely mounted upon said boss 16^a of the arm 16 is a gage arm 22 carrying the front gage 23 and having projecting therefrom lugs 24, 25 to the former of which is fulcrumed by the pivot 26 an angle lever 27, 28, while the lug 25 serves as a mounting for a swivel block 29 screw threaded for engagement by a screw 30 mounted within a similar swivel block 31 and bearing a worm wheel 32. Fulcrumed on the gage arm 22 by the pivot 33 is an angle lever 34, 35. The arm 28 of the first mentioned angle lever carries a roller 36 adapted to travel on the cam 20 while the arm 34 of the other angle lever carries a roller 37 adapted to travel on the cam 21. To the arm 27 of the first angle lever is connected by means of a pin 38 and a slot 39 an arcuate shoe 40 extending horizontally from another arm 41 which is likewise loosely mounted upon the boss 16^a. To the extreme front end of the shoe 40 is pivoted at 42 by means of a link 43 and a second pivot 44 the lower end 45 of a rod 46 which latter is mounted to slide within a swivel block 47 mounted at 48 in the outer end of the arm 35 of the second angle lever. The link 43 has projecting beyond its pivot 42 a flipper 49 the purpose of which will hereinafter be made clear. A spring 50 serves to hold the roller 36 against its cam while a similar spring 50^a serves the same purpose with reference to the roller 37.

It should be understood that the shaft 13 extends the full width of the press and that a counterpart of the mechanism above described is mounted upon the shaft 13 and the rod 19 near the two sides of the press, that is to say separated a distance slightly less than the width of the paper to be fed, so that a front gage is provided for effecting register of the sheets at the front edges and adjacent each side. The arms 16 are slidable longitudinally upon the shaft 13 so as to properly position the two registering mechanisms in order to act upon the sheet.

at the proper point. The position of each having been determined, the arm 16 is clamped upon the shaft 13 by means of the set screw device 16^b acting in an obvious manner. The worm wheel 32 of the screw 70 30 may be then manipulated by hand in order to position the gage arms 22 on the two mechanisms in exact transverse alignment and in the proper position longitudinally to effect the proper front register of 75 the sheet.

The press being in motion, the gage arm 22 revolves and carries with it the front gage 23 at a peripheral speed corresponding exactly to that of the grippers upon the impression cylinder by reason of its being tied to the arm 16 by means of the screw 30. The angle levers 27, 28 and 35, 36 likewise revolve with the arm 22, being fulcrumed thereto respectively at 26 and 33. 85

As the sheet S is fed to the press by the sheet feeder (not shown) its front edge comes against the front gage 23 or approximately in that position, usually within a sixteenth to a quarter of an inch therefrom. 90 The roller 37 riding upon the cam 21 acts through the lever 34, 35 compressing the spring 46^a and thus resiliently acting upon the links 43 and the flipper 49 whereby the latter is closed upon the forward end of the sheet S frictionally gripping the same between the flipper and the lower face of the shoe 40, the degree of said spring pressure being regulable by means of the knurled nuts 46^b. Immediately thereafter the roller 190 36 riding upon the cam 20 moves the angle lever 27, 28 thereby advancing the shoe 40 and the flipper 49 relative to the gage arm 22 and the gage 23, the gage traveling at the speed of the grippers and the shoe 40 at a 195 slightly greater speed by reason of the action of the lever. The sheet gripped at its forward edge between the flipper 49 and the shoe 40 is likewise advanced until it comes in contact with the gage 23 whereupon meeting with this obstruction the sheet continues 110

ing with this restriction the sheet continues its movement at the speed of the gage while the shoe 40 and the flipper 49 moves at a faster speed. The front gage 23 continues its movement at the speed of the grippers on the impression cylinder, the sheet being held against the shoe 40 and abutting the gage 23 by the flippers 49 until the grippers on the impression cylinder have gripped the forward end of the sheet. This transfer takes place on the tangent point of the shoe 40 with the impression cylinder 11 so that the flipper 49 and the grippers 12 can both be on the sheet at the tangent point and in fact an instant later. During the next one-eighth inch travel of the cylinder beyond the tangent point, the shoe 40 has moved the flipper forward out from under the sheet so that the latter is free to continue its path on the impression cylinder. The roller 37 then

clears the high part of cam 21 and the flipper 49 is opened by the action of the spring 50^a and is then ready to receive the next sheet as it comes into position. Similarly 5 roller 36 clears the high part of cam 20 and spring 50 restores the lever to its original position with the shoe 40 retracted as indicated, ready for the next cycle.

As previously stated, the worm wheel 32 upon the spindle 30 may be manipulated by hand in order to obtain an approximate adjustment of the front register 23. The press being in motion, however, and it being ascertained that the sheets are not exactly in 15 register, mechanism is provided for acting upon the worm wheel 32 in order to adjust the front register without stopping the press. Such mechanism may be described as follows:

20 Fixedly mounted on the arm 16 are a pair of magnets 51—52 arranged with their axes in oblique relation to each other in the plane of a ratchet wheel 53 and upon each side of the same. The ratchet wheel 53 is mounted 25 upon a worm shaft 54 carrying the worm 54^a which is in mesh with the worm wheel 32 upon the screw spindle 30. The armature core 55 of the magnet 51 and the armature core 56 of the magnet 52 each carries a pivoted pawl 57—58, the noses of which are adapted to engage the teeth of the ratchet wheel 53. The pawls are normally pressed into engagement with the ratchet wheel by 30 means of the springs 59—60, but in the extended position of the armature coils 55—56 the pawls are acted upon by the stationary pin 61 and are thereby pressed out of engagement with the ratchet wheel.

The magnet cores 55—56 are normally 40 held in the position shown with their pawls out of engagement with the ratchet wheel 53 by means of the springs 63—64. The two magnets 51, 52 are in independent electric circuit indicated in Fig. 1. A battery is 45 illustrated at 65 from which parallel circuits 66—67 including switches 68—69 lead to brushes one of which is illustrated at 70 in Fig. 2. The brushes are counterparts of each other and travel upon collector rings 50 71, 72, mounted upon the insulated collar 73. The collector ring 71 connected by means of the wire 75 with the magnet 51 while the collector ring 72 is connected by means of the wires 76 with the magnet 52. Both of 55 the magnets are grounded as indicated at 77 on the press.

With reference particularly to Figs. 2 and 3 of the drawings it will be clearly understood that if one of the magnets 51 or 52 be 60 energized by the closing of its switch 68 or 69 as the case may be, the armature of the magnet will be withdrawn and its pawl will engage with the ratchet wheel 53 turning with the same the extent of one notch, and 65 upon the deenergization of the magnet by

the opening of the switch its core will be again extended and its pawl brought out of engagement with the ratchet wheel by means of the pin 61. The operation will be repeated as often as the switch is closed. The 70 switches 68—69 may be advantageously in the form of push buttons and so long as one of these buttons is repeatedly pressed the armature of the magnet will act upon the ratchet wheel 53 to turn the same step by 75 step. The turning of the ratchet wheel 53 and its worm shaft 54 acts through the worm 54^a upon the worm wheel 32 to turn the screw spindle 30 and thereby advance or retract the front gage 23. 80

It will thus be observed that the operator having his eye upon the sheets passing through the press and determining that the front gage should be moved backward or forward to insure proper register may press 85 upon the appropriate switch button 68 or 69 and thereby effect the advancement or the retraction of the front gage, without stopping the press and with the greatest nicety.

Side register.

90

Upon the shaft 13 outside the mechanism for effecting front register of the sheet as above described, is a similar organization of mechanism for effecting side register of the 95 sheet (Figs. 5 and 6). Herein the side gage arm 80 is keyed to the shaft 13 by means of an extended boss 80^a, and a similar collar 17^a is loosely mounted upon the boss 80^a and held in stationary position by means of the 100 arm 18^a embracing as before the shaft 19. This collar is provided with a cam 81 in one plane and another cam 82 in a different plane. The side gage arm 80 carries the side 105 gage 84, the position of which is adjustable transversely of the press and longitudinally of the shaft 13 by means of a spindle 85 journaled at 86 and 87 in a bearing arm 78 clamped on the rod 19 by the clamp screw 89, the spindle having a ratchet head 90 and 110 provided with worms 91, 92 in mesh respectively with worm wheels 93, 94 on shafts 95, 96 transversely journaled in the bearing arm 88 and having their ends in threaded engagement at 97, 98 with the arm 18^a. 115

Transversely slidable within the gage arm 80 is a shoe 99 carrying a roller 100 which works within an oblique slot 101 of an angle lever 102, 103, the opposite arm of which lever has a roller 104 arranged to 120 travel upon the cam 81. The other end of the shoe 99 opposite the roller 100 has pivoted thereto at 105 an arm 106 connected by means of a rod 107 with a link 108 pivoted at 109 to the shoe 99, which link 108 125 is extended to form a flipper 110. The rod 107 is surrounded by a compression spring 111, the tension of which is adjustable by means of the knurled nut 112. A coil spring 113 much stiffer than 111 holds the 130

stop 114 of the arm 106 against the shoe 99. The angle lever 102, 103 is fulcrumed to the gage arm 80 upon a pivot 115, and similarly pivoted to said arm at 116 is an angle lever 117, 118, the arm 118 of which is provided with a roller 119 arranged to ride upon the cam 82, while the opposite arm 117 of said lever has an offset portion provided with an inclined face 120 adapted to engage the arm 106 whereby to open and close the flipper 110.

In use, the flipper 110 is normally closed, being held in this position by the tension of the springs 111 and 113. As the sheet is approached approximately to the gage 23 for front register as previously described the cam roller 119 rides upon the cam 82 opening the flipper 110 to allow the side edge of the sheet to pass and to offer no hindrance to the action of the front register. Front register having been obtained the roller 119 rides off the cam 82 closing the flipper 110 upon the sheet S at the side thereof. Shortly thereafter the roller 104 rides upon the cam 81 bringing the oblique slot 101 to bear through the roller 100 upon the shoe 99, drawing the sheet 53 to the left, as shown in Fig. 6, against the side gage 84, the flipper sliding upon the sheet during the further lateral movement of the flipper and shoe after the side registration of the sheet.

At the moment the grippers of the impression cylinder close on the sheet, the flipper 110 still has hold of the sheet and during the next one-eighth inch of travel of the cylinder, the flipper slips off the sheet and allows it to pass freely to the impression cylinder. The flipper then remains closed until the next cycle starts. After the sheet is taken the roller 104 rides off of high part of cam 81 bringing the shoe 99 back to its starting position.

If the pressman finds that the side register is imperfect due to the side gage being inaccurately positioned laterally of the sheet path, he may leave his position and manually turn the ratchet head 90 of the shaft 85 left or right as may be indicated and thus through the worms 91, 92 and the worm wheels 93, 94 acting through the shaft 95, 96 shift the collar 17^a and with it the side gage 84 into a proper position so that the register is perfect. However, in order that this shifting of the side gage may proceed step by step and be effected by the pressman without leaving his position where he can have the sheets under his eye, electro-magnetic means are provided for shifting the ratchet wheel 90 and the shaft 85 as follows:

Upon the bracket 125 is mounted a pair of counterpart magnets 126 arranged similarly to the positions hereinbefore described with reference to the front register, with

their axes inclined to each other in an oblique relation and with their armature cores similarly provided as previously described with pawls for engagement with the ratchet wheel 90. These magnets are similarly in independent electric circuits controlled by a push-button switch so that either of them may be repeatedly energized in order to turn the ratchet wheel 90 in one direction or the other whereby to retract or advance the side gage relative to the sheet travel path.

It will thus be seen that the pressman may adjust both the front and side gages step by step without leaving his position where he can most advantageously view the sheets as they pass through the machine in order to determine whether or not the registration is correct and if not what adjustment is required to bring about proper register.

In order to effectually guard the wiring against entanglement or damage during the revolving motion of the gage arms and magnets, the same is illustrated in Figs. 1 and 2 as extending from a collector ring to the magnet through bores 75^a and 76^a respectively formed in the hub 16^a about the shaft 13. Other ways for carrying these wires may obviously be devised with, some sacrifice of compactness and safety and yet without materially detracting from the efficiency of the invention.

I claim:

1. The combination of means for imparting front register to a sheet fed to a printing couple having grippers comprising a gage-support moving forwardly with the sheet, a gage adjustably connected to the support, and stationary means to vary the adjustment of said connection whereby to adjust the position of the gage while the press is in motion, and comprising a pair of electro-magnets moving with the sheet and oppositely acting upon the gage, and independent means for energizing either one of the magnets at will.

2. The combination of means for imparting front register to a sheet fed to a printing couple having grippers comprising a gage-support moving forwardly with the sheet, a micrometer connection between the gage and support, and stationary means to actuate the micrometer mechanism to vary the adjustment of said connection whereby to advance or retard the position of the gage while the press is in motion and comprising a ratchet wheel, a pair of magnets arranged on opposite sides of the ratchet wheel and having pawl connections therewith, and independent means for energizing either one of magnets at will.

3. The combination of means for imparting front register to a sheet fed to a printing couple having grippers comprising a gage-support moving forwardly with the

- sheet, a micrometer connection between the gage and support, and stationary means to actuate the micrometer mechanism to vary the adjustment of said connection whereby 5 to advance or retard the position of the gage while the press is in motion and comprising a worm wheel upon the micrometer shaft, a worm shaft in mesh with the worm wheel, a ratchet wheel upon the worm shaft, 10 a pair of magnets arranged with their axes in substantially the plane of the ratchet wheel and upon opposite sides thereof, pawls carried by the magnet cores and arranged to engage the teeth of the ratchet wheel in one direction of movement and to clear the same in the other direction, and independent means for energizing either one of the magnets at will.
4. The combination of means for imparting register to a sheet fed to a printing couple having grippers comprising a gage-support, a gage adjustably connected to the support and revoluble at the speed of the cylinder grippers, and stationary means to 20 vary the adjustment of said connection whereby to adjust the position of the gage while the press is in motion, said adjusting means comprising a screw spindle connecting the gage support and gage, a worm shaft, a worm on said shaft in engagement with the screw spindle, a ratchet wheel on said worm shaft, a pair of magnets arranged on opposite sides of said shaft with their axes at an oblique inclination to each other 30 and in substantially the plane of the ratchet wheel, pawls carried by the armature cores of said magnets, said pawls arranged to engage opposite sides of the ratchet wheel as the armature core is actuated by the 40 energization of its magnet, and independent means for energizing either one of the magnets at will.
5. The combination of means for imparting register to a sheet fed to a printing couple having grippers comprising a gage-support, a gage adjustably connected to the support and revoluble at the speed of the cylinder grippers, and stationary means to vary the adjustment of said connection 45 whereby to adjust the position of the gage while the press is in motion, said adjusting means comprising a screw spindle connecting the gage and gage support, a worm wheel on said screw spindle, a worm shaft, a worm 50 on said shaft in engagement with the worm wheel, a ratchet wheel on the worm shaft, a pair of magnets arranged one on each side of the worm shaft with their armature cores substantially in the plane of the ratchet 55 wheel, a pawl carried by each of the armature cores, a spring pressing each of said pawls normally into engagement with opposite sides of the ratchet wheel, means for retracting said pawl out of engagement 60 against the operation of the spring, inde-
- pendent electric circuits one for each of said magnets, a push-button switch in each of said circuits whereby either of the magnets may be energized independently of the other at will in order to rotate the ratchet 70 wheel in either one of two directions.
6. The combination of means for imparting register to a sheet fed to a printing couple having grippers comprising a gage-support, a gage adjustably connected to the support and revoluble at the speed of the cylinder grippers, and stationary means to vary the adjustment of said connection whereby to adjust the position of the gage while the press is in motion, said adjusting 75 means comprising a screw spindle connecting the gage and support, a ratchet wheel operatively connected with the screw spindle, a pair of magnets arranged on opposite sides of the ratchet wheel with their armature cores in substantially the plane thereof, pawls carried by the armature cores and arranged to act upon opposite sides of the ratchet wheel, and means for energizing the magnet independently at will in order to 80 rotate the ratchet wheel in one of two directions comprising independent electric circuits each including a collector ring mounted upon the hub of the gage support and also including a push button switch. 85
7. The combination of means for imparting register to a sheet fed to a printing couple having grippers comprising a gage-support, a gage adjustably connected to the support and revoluble at the speed of the cylinder grippers, and stationary means to vary the adjustment of said connection whereby to adjust the position of the gage while the press is in motion, said adjusting means comprising a screw spindle connecting the gage and support, a ratchet wheel operatively connected with the screw spindle, a pair of magnets arranged on opposite sides of the ratchet wheel with their armature cores in substantially the plane thereof, pawls carried by the armature cores and arranged to act upon opposite sides of the ratchet wheel, and means for energizing the magnet independently at will in order to 90 rotate the ratchet wheel in one of two directions comprising independent electric circuits each including a collector ring mounted upon the hub of the gage support and also including a push button switch. 95
10. The combination of means for imparting register to a sheet fed to a printing couple having grippers comprising a gage-support, a gage adjustably connected to the support and revoluble at the speed of the cylinder grippers, and stationary means to vary the adjustment of said connection whereby to adjust the position of the gage while the press is in motion, said adjusting means comprising a screw spindle connecting the gage and support, a ratchet wheel operatively connected with the screw spindle, a pair of magnets arranged on opposite sides of the ratchet wheel with their armature cores in substantially the plane thereof, pawls carried by the armature cores and arranged to act upon opposite sides of the ratchet wheel, and means for energizing the magnet independently at will in order to 100 rotate the ratchet wheel in one of two directions comprising independent electric circuits each including a collector ring mounted upon the hub of the gage support and also including a push button switch. 105
11. The combination of means for imparting register to a sheet fed to a printing couple having grippers comprising a gage-support, a gage adjustably connected to the support and revoluble at the speed of the cylinder grippers, and stationary means to vary the adjustment of said connection whereby to adjust the position of the gage while the press is in motion, said adjusting means comprising a screw spindle connecting the gage and support, a ratchet wheel operatively connected with the screw spindle, a pair of magnets arranged on opposite sides of the ratchet wheel with their armature cores in substantially the plane thereof, pawls carried by the armature cores and arranged to act upon opposite sides of the ratchet wheel, and means for energizing the magnet independently at will in order to 110 rotate the ratchet wheel in one of two directions comprising independent electric circuits each including a collector ring mounted upon the hub of the gage support and also including a push button switch. 115
12. The combination of means for imparting register to a sheet fed to a printing couple having grippers comprising a gage-support, a gage adjustably connected to the support and revoluble at the speed of the cylinder grippers, and stationary means to vary the adjustment of said connection whereby to adjust the position of the gage while the press is in motion, said adjusting means comprising a screw spindle connecting the gage and support, a ratchet wheel operatively connected with the screw spindle, a pair of magnets arranged on opposite sides of the ratchet wheel with their armature cores in substantially the plane thereof, pawls carried by the armature cores and arranged to act upon opposite sides of the ratchet wheel, and means for energizing the magnet independently at will in order to 120 rotate the ratchet wheel in one of two directions comprising independent electric circuits each including a collector ring mounted upon the hub of the gage support and also including a push button switch, the wires leading from the collector rings through longitudinal channels formed in the hub of the gage support to a proper connection with each of the magnets. 125

In testimony whereof I have hereunto signed my name in the presence of two subscribing witnesses.

JOSEPH R. BLAINE.
